REAR OIL SEAL FOR JOURNAL BOXES

Charles S. Bohmer, Hillsboro, Ill., assignor to Railway Car Equipment Co., Hillsboro, Ill., a corporation of Illinois

Filed Aug. 4, 1959, Ser. No. 831,653

2 Claims. (Cl. 277—174)

This invention relates generally to railroad car journal boxes and concerns more particularly a rear oil seal for use in such boxes.

Journal boxes of the type commonly used for supporting a railroad car on its axles are conventionally provided with a sealing device adapted to snugly surround the axle "dry seat", or fillet portion, at the point where the axle enters the journal box. The sealing device thus seals off the opening through which the axle enters the journal box, preventing dust and other foreign material from entering the box while retaining lubricant therein for lubricating the supporting bearing or "brass". Conventional journal boxes have a vertical slot or groove at the point where the axle enters the box, called the dust guard "well", which is adapted to receive and retain a rear oil seal in proper position.

Seals of this type are subject to very hard usage during normal operation since the axle journal of a railroad car does not remain exactly centered with respect to the journal box when the car is running. Indeed, an axle journal and journal box may shift relative to one another a distance of over $1\frac{1}{2}$ inches when the car's brakes are applied or the car is otherwise jolted, and it has been observed that the journal brass will jump up to $\frac{3}{4}$ of an inch above the axle journal when track imperfections are encountered at high speeds. Thus, not only is the axle rotating quite rapidly within the rear oil seal, but the axle will also be frequently jarred laterally and down into the body of the seal.

It is therefore an object of the invention to provide a rear oil seal for standard journal box assemblies which readily accommodates relative axle-journal box movement while minimizing the likelihood of the seal being unseated from the dry seat or fillet portion of the axle journal.

It is an equally important and related object to provide a seal as characterized above that, in the event the seal is separated from the axle dry seat, permits the parts to regain their normal sealing relationship without crushing or jamming the seal against the rough cast wall surface of the journal box.

Another object of the invention is to provide a rear oil seal of the above type which fits easily and snugly into tight sealing engagement with journal box dust guard wells of varying width.

A further object of the invention is to provide a rear oil seal having the above advantages which is quite economical to manufacture in that it requires a minimum amount of material and can be quite simply formed.

Other objects and advantages of the invention will become apparent upon reading the following detailed description and upon reference to the drawings in which:

FIGURE 1 is a longitudinal section of a conventional railroad journal box assembly in which a rear oil seal constructed according to the present invention has been installed;

FIG. 2 is a transverse section taken along the line 2—2 in FIG. 1; and

FIG. 3 is a section taken along the line 3—3 in FIG. 2.

While the invention will be described in connection with a preferred embodiment, it will be understood that I do not intend to limit the invention to that embodiment. On the contrary, I intend to cover all alternatives, modifications and equivalents as may be included within the

2

spirit and scope of the invention as defined by the appended claims.

Turning first to FIG. 1, there is shown a railroad journal box 10 including a hinged front cover 12 and a circular aperture 13 formed in a double rear wall 14. Extending through the aperture 13 is an axle 15 which includes a journal portion 16 and a fillet portion or dry seat 17. Resting on top of the journal 16 is the conventional supporting bearing structure or brass 20. It will be understood that the axle journal 16 is free to revolve beneath the bearing 20 and that the bearing, through the journal box 10, transfers the weight of the railroad car to the axle 15.

For the purpose of conveniently mounting a rear oil seal in the rear of the journal box 10, the journal box 15 rear wall 14 is provided with a dust guard well 22 generally of U-shaped outer configuration as can be seen in FIG. 2. The parts are so proportioned that the dry seat 17 of the axle 15 is disposed in the plane of the dust guard well 22 when the axle and the journal box 10 are in their normal relative positions.

Providing a rotary seal enclosing the rear of the journal box 10 is a rear oil seal 30, embodying the present invention, which is fully bottomed within the dust guard well 22 and which has an annular sealing edge 30a snugly engaging the periphery of the axle dry seat 17. The seal 30 is a unitary body formed of resilient material having a continuous outer thickened portion or rim 31 shaped to fit snugly within the well 22, an inner thickened portion or ring 32 slightly distended about the axle dry seat 17 so as to maintain a firm sealing contact therewith, and a relatively thin web portion 33 joining the rim 31 and the ring 32 and forming a barrier closing and sealing the opening 13.

The seal 30 is not symmetrical when viewed in longitudinal section, and therefore the seal has a wheel side 33a and a box side 33b facing, respectively, the wheel (not shown) on the axle 15 and the journal box 10.

Pursuant to the invention, the web portion 33 joins the rim 31 closely adjacent the wheel side 33a of the seal 30 and the web is folded once at 34 completely about its periphery toward the box side 33b of the seal. The web 33 joins the ring 32 at the box side of the latter.

The effect of this arrangement is to dispose the ring 32 toward the wheel side 33a of the seal 30. The fold 34 provides flexibility between the rim 31 and the ring 32 and allows free relative movement between these parts in all directions but that direction in which the ring tends to move toward the box side 33b of the seal. In other words, considering the rim 31 to be held steady, the ring 32 can be easily moved up, down and to the right in FIG. 1, and from side to side in FIG. 2, through the flexibility in the fold 34. But movement of the ring 32 to the left in FIG. 1 can only be accomplished by stretching the material forming the web 33. Thus, movement of the ring 32 toward the box side 33b of the seal is resisted by the seal construction.

The importance of providing flexibility between the ring 32 and the rim 31 will be obvious to those skilled in the art. This flexibility allows relative movement between the axle and the journal box without damage to the seal 30 and without affecting its sealing effectiveness.

The importance of disposing the ring 32 toward the wheel side 33a of the seal 30 is that this minimizes the tendency of the ring to drop from the dry seat 17 since the edge 17a of the dry seat is as far away as possible from the normal position of the ring 32. Thus, a maximum amount of axial relative movement between the journal box and the axle is permitted before the ring 32 becomes unseated from the dry seat 17.

Although the ring 32 is kept as far as possible from the edge 17a of the dry seat 17, experience has shown that

relative movement between the axle and the journal box is often sufficient to unseat the ring 32 from the dry seat. Such relative movement between the axle and the journal box could occur, for example, when the railroad car swings around a relatively sharp curve in the track so that the car, and hence the journal box 10, slides to the left in FIG. 1 relative to the axle 15. If this movement is sufficient, the ring 32 will be carried over the edge 17a of the axle dry seat. Such extreme movement is always a temporary condition and the journal box 10, after shifting to the left, is usually slammed back to the right.

When the above described action occurs, it can be seen that to re-establish the normal position of the parts, the dry seat 17 must be forced within the ring 32, or more accurately, the ring 32 must be forced over onto the dry seat 17. Since the seal 30 is constructed so that movement of the ring 32 toward the box side of the seal is strongly resisted by the seal itself, it can be seen that the ring 32 can be drawn over the edge 17a and onto the dry seat 17 without jamming the web 33 against the rough cast walls of the journal box. Stated another way, the seal 30 itself provides the required stiffness to permit the ring 32 to move up onto the dry seat 17. Therefore, the web 33 is not jammed against the rough cast walls of the journal box when the ring 32 is forced onto the axle dry seat 17.

In accordance with a further aspect of the invention, the rim 31 is formed with oppositely projecting ridges 41 and 42 which are arranged about the lower portion of the rim to achieve snug sealing engagement with the walls of the well 22, even though the width of the well 22 may vary through a very wide range. It should be understood that conventional railroad journal boxes such as the box 10 are formed by casting and it is common experience to set permissible tolerances for the width of the well 22 at as much as plus or minus $\frac{1}{16}$ of an inch. The rim 31 must thus be able to snugly and easily fit within dust guard wells whose width might vary at least as much as $\frac{1}{16}$ of an inch.

To achieve this result, the rim 31 is formed with a thickness that is less than the smallest well width likely to be encountered, the ridges 41 and 42 are extracted sufficiently far so that the combined thickness of the rim 31 and the ridges 41 and 42 is greater than the widest guard well likely to be encountered, and the ridges 41 and 42 are laterally offset with respect to one another. The effect of this construction is best shown in FIG. 3. When the rim 31 is pushed downwardly into a dust guard well, the offset ridges are squeezed between the opposed walls of the well and act to twist the rim 31 by slightly distorting the resilient material forming the rim. The fact that the rim 31 is flexibly distorted as it is inserted into the well 22 permits the seal 30 to be moved into place without jamming. The slight twist of the rim 31, dependent upon the thickness of the well 22, assures that the offset ridges 41, 42 are urged into snug engagement with the opposite side walls of the well 22, even though the spacing of these walls may vary.

In order to stiffen the outer shape of the seal 30 and rigidify the rim 31, a steel reinforcement 45 is embedded within the rim 31. To stiffen and rigidify the circular shape of the ring 32, a second steel reinforcement 46 is embedded within the material forming the ring 32.

It is contemplated that the seal 30 be molded as a single unit from a suitable oil resistant, resilient material, such as Buna-N, a synthetic rubber sold under the trade name "Hycar." The molding operation required to form the seal 30 is relatively simple because of the uncomplicated configuration of the seal 30. Those skilled in the art will also appreciate that very little material is required to form the seal 30 and hence, for this further reason, the seal may be very inexpensively manufactured.

I claim as my invention:

1. As an article of manufacture, an oil seal comprising an integrally molded unit of flexible material including an outer thickened portion shaped to fit within a journal box dust guard well, said outer portion being thinner than the smallest allowable width of a standard railroad journal box dust guard well, an inner thickened portion circular in outline for surrounding an axle dry seat in sealing engagement, a relatively thin portion connecting said inner and outer portions, and integral projecting sealing ridges extending one from each side of said outer portion so that the overall thickness of the outer portion and its ridges is greater than the largest allowable width of a standard dust guard well, said ridges being laterally offset one from the other on said outer portion so that insertion of the unit into a dust guard well causes the outer portion to twist slightly to accommodate the width of the well with the sealing ridges snugly engaging the opposite well walls without jamming.

2. As an article of manufacture, an oil seal comprising an integrally molded unit of resilient material including an outer thickened portion shaped to fit within a journal box dust guard well, an inner thickened portion circular in outline for surrounding an axle dry seat in sealing engagement, a relatively thin portion connecting said inner and outer portions, said unit having a wheel side and a box side to be disposed, when installed, facing the wheel and journal box respectively, said thin portion joining said outer portion closely adjacent the wheel side of the unit and being folded only once toward said box side completely about its periphery so as to dispose said inner portion at the wheel side of said unit, said single fold allowing free relative movement between said inner and outer portions in all directions but that in which the inner portion tends to move toward the box side of the unit, and integral projecting sealing ridges extending one from each side of said outer portion so that the overall thickness of the outer portion and its ridges is greater than the largest allowable width of a standard dust guard well, said ridges being laterally offset one from the other on said outer portion so that insertion of the unit into a dust guard well causes the outer portion to twist slightly to accommodate the width of the well with the sealing ridges snugly engaging the opposite well walls without jamming.
